United States Patent Office

Des. 210,670
Patented Apr. 2, 1968

210,670

PORTABLE LECTERN

Charles J. Eddy, 485 Vern Drive,
Clearfield, Utah 84015

Filed May 26, 1966, Ser. No. 2,437

Term of patent 14 years

(Cl. D33—7)

FIG. 2

FIG. 1

FIG. 3

FIGURE 1 is a rear perspective view of a portable lectern showing my new design as it appears in the open or operative position, the side opposite thereto being a mirror image of the side shown;

FIGURE 2 is a front perspective view thereof; and,

FIGURE 3 is a side elevational view thereof as it appears in closed and carrying position with the undisclosed side being a mirror image thereof.

I claim:

The ornamental design for a portable lectern, as shown and described.
